COMBINED STAPLER, PAPER PUNCH OR THE LIKE

Chester J. Abend, Camillus, and Jack R. Goodrich, East
Syracuse, N.Y., assignors to SCM Corporation, a cor-
poration of New York

Filed June 29, 1962, Ser. No. 70,735

Term of patent 14 years

(Cl. D74—1)

Fig. 1
Fig. 2

FIG. 3

FIG. 4

FIG. 5

FIG. 6

FIGURE 1 is a perspective view of the combined stapler, paper punch or the like showing our new design;

FIGURE 2 is a top plan view thereof;

FIGURE 3 is a front elevational view thereof looking toward the stamping mechanisms, and the clip dispenser;

FIGURE 4 is a rear elevational view thereof looking toward the paper punch;

FIGURE 5 is a right-side elevational view thereof looking toward the tape dispenser; and

FIGURE 6 is a left-side elevational view thereof looking toward the side of the stapler.

We claim:

The ornamental design for a combined stapler, paper punch or the like, substantially as shown.
